UNITED STATES PATENT OFFICE.

WILLIAM G. STEEN, OF PITTSBURGH, PENNSYLVANIA.

TOY.

1,259,923.

Specification of Letters Patent. Patented Mar. 19, 1918.

Application filed August 2, 1917. Serial No. 184,050.

To all whom it may concern:

Be it known that I, WILLIAM G. STEEN, a citizen of the United States of America, residing at Pittsburgh, in the county of Allegheny and State of Pennsylvania, have invented certain new and useful Improvements in Toys, of which the following is a specification.

This invention relates to toys, more particularly sand toys, and has for its object to provide, in a manner as hereinafter set forth, a toy of such class with means to constitute miniature loading, elevating, conveying and dumping mechanisms for automatically loading and elevating sand at one point or station and then conveying it to and dumping it at another point or station providing thereby an instructive and amusing toy for children.

Further objects of the invention are to provide a toy for the purpose set forth which is comparatively simple, in its construction and arrangement, strong, durable, efficient in its use, readily assembled and disassembled, automatic in its operation, and comparatively inexpensive.

With the foregoing and other objects in view the invention consists of the novel construction, combination and arrangement of parts as hereinafter more specifically described and illustrated in the accompanying drawings, wherein is shown an embodiment of the invention, but it is to be understood, that changes, variations and modifications can be resorted to which come within the scope of the claims hereunto appended.

In the drawings wherein like reference characters denote corresponding parts throughout the several views:

Figure 1 is a vertical sectional view on line I—I Fig. 4.

Fig. 2 is a side elevation of the loading station, parts broken away for the sake of clearance.

Fig. 3 is a side elevation of the dumping station.

Fig. 4 is a sectional plan on line IV—IV Fig. 1.

Fig. 5 is an enlarged sectional elevation 50 of the combined loading and dumping mech-

anism showing the association therewith of the hopper and dumping conveyer during loading of the latter.

Fig. 6 is a sectional detail of a part of the combined loading and elevating mechanism. 55

Fig. 7 is a like view of another part of the combined elevating and lowering mechanism.

The toy comprises a loading station including a normally closed hopper, a combined loading and elevating mechanism for a dumping conveyer, a shiftable track, a dumping conveyer traveling on the track and a dumping station connected with the loading station by the track. 60 65

The loading station represents a grain elevator 1, provided with windows in its front, rear and inner side walls. The outer side walls are cut away to provide a vertically disposed elongated opening 2, so that access can be had to the interior of the loading station. The inner side wall is cut away to provide a vertically disposed elongated opening 3, to permit of the shifting movement of a conveyer track and the traveling 70 75 of a conveyer on said track into and out of the loading station. The conveyer and its track will be presently referred to.

The reference character 4 denotes a tray arranged below the loading station, as well 80 as being spaced therefrom. Uprights 5 are provided for supporting the loading station and which have their lower ends secured within the tray or trough 4.

Arranged within the loading station 1, at 85 one side of its upper portion, is a loading hopper 6, which receives a supply of sand fed through the top of the loading station 1. The hopper 6 extends from the inner side wall of the loading station to a point removed from the outer wall. The inner side of the bottom of the hopper 6 is provided with a chute 7, which terminates at one end in a discharge spout 8, normally closed by a cut off 9, carried by a pivoted yoke 10, 90 attached to the sides of the chute 7. A trip arm 11, is connected to one of the arms of the yoke 10, and which is adapted to be engaged and actuated by a vertically movable element, to be presently described, for the 95 100

purpose of shifting the cut-off 9 clear of the spout 8 to allow discharge from the hopper 6.

Connected to the bottom of and extending 5 downwardly at an inclination with respect to the chute 7 is a conducting chute 12, which projects beyond, as well as being spaced from the spout 8, so as not to interfere with the movement of the cut-off 9, when the latter is shifted to open the spout 8, or when 10 said cut-off 9 moves to normal position by gravity to close the spout 8.

The chute 12 has its discharge end 13 arranged so that the material discharged 15 from the hopper into the chute 12 will be conducted into a vertically movable element to be presently referred to.

The chute 12, in proximity to the discharge end 13, thereof, has projecting laterally therefrom a downwardly inclined chute 14, which deflects a part of the material passing through the chute 12, into a dumping conveyer to be presently referred to.

25 The combined elevating and lowering mechanism which associates with the hopper 6 and conducting chute 12 consists of three upright rods 15, 16, and 17, arranged in parallelism and with the rod 15 nearer to the rod 16 than the position of the rod 16 with respect to the rod 17. The upper ends of the rods 15, 16, 17, are connected together by a cross-head 18, provided at its bottom with a flange 19 having openings 20, 21. The cross-head 18 is secured to the upper portion of the hopper 6 and has fixed thereto a bracket 22, which in connection with the cross-head 18 supports the shafts 23, of a pair of pulleys 24. Traveling over 30 the pulleys 24 and through the openings 20, 21 is an elevating and lowering cable 25.

Each of the rods 16, 17, is provided with a pair of guides 26, for the lateral extensions 27 of a vertically movable element 28, 45 which is in the form of a dumping bucket and has connected to its top a bail 29, having an eye 30, to which one end of the cable 25 is connected.

The trip arm 11 is arranged in the path 50 of the bail 29 whereby when the element 28 is elevated, the bail 29 will engage the trip arm 11 and shift the yoke 10, outwardly, under such conditions carrying the cut-off 9 therewith to open the spout 8, so that the 55 contents of the spout will be discharged into the conducting chutes 13 and 14. The chute 13 conducts the material into the element 28 and the chute 14 into the dumping conveyer, to be presently referred to.

60 Secured to a pair of the uprights 5, is a cross-brace 31, having inwardly extending supports 32, for the lower ends of the rods 15, 16, 17. The cross-brace 31 is positioned in the path of a strip arm 33, attached to a

yoke 34, which carries a cut-off 35, for closing a spout 36, depending from the conical bottom 37 of the element 28. The yoke 34 is pivotally connected to a pair of ears 38, which depend from the bottom 37. By the foregoing arrangement of parts it is obvious that when the element 28 moves downwardly, due to the weight of the sand supplied thereto from the hopper 6, the trip arm 33 will be actuated and the material carried by the element 28, will be discharged 75 into the tray 4, from which it is removed manually and supplied to the hopper 6.

Arranged between the rods 15, 16, is a vertically movable track shifting slide 39, having lateral guide-arms 40, which straddle the rods 15, 16. The slide 39, near its upper end is provided with an opening 41, for a purpose to be presently referred to, and said slide 39 at its top has an eye 42, to which is secured the other end of the 85 cable 25.

The shiftable conveyer track, which is preferably formed of two sections, for convenience in packing, is indicated by the reference character 43, and at each end is provided with an angle-shaped top arm 44 which are oppositely disposed with respect to each other. One end of the track 43 is provided with a depending hook 45, and its other end is provided with a depending hook 45. The hook 45, straddles the bottom wall of the opening 41, in the slide 39, whereby the track will be connected to said slide. The function of the hook 45 will be presently referred to.

The dumping conveyer is in the form of a bucket 47, having a discharge spout 48 normally closed by a cut-off 49, carried by a yoke 50. The arms of the yoke 50 are pivotally connected to brackets 51, secured to the sides of the bucket 47. Depending from the cut-off 49, as well as being secured to an extension 52, of the yoke 50, is a curved trip arm 53, which when actuated will move the cut-off 49, clear of the spout 48, so that the contents of the bucket 47 can be discharged.

The bucket 47 is provided at its top with a pair of bails 54 which are connected to the sides of a trolley 55, the latter being mounted upon the track 43.

The dumping station, which is indicated at 56, is formed from a structure consisting of sides, front and rear walls, a top, and a base, the base in the form of a hopper 57, having a discharge spout 58 normally closed by a cut-off 59, carried by a yoke 60, which is pivotally connected with the spout 58. A handle bar 61 is attached to one of the arms of the yoke 60, for the purpose of shifting the latter to swing the cut-off 59, clear of the spout 58, so that the contents of the hopper 57 will be discharged.

The dumping station 56 has the front and rear walls provided with windows. The station 56 has its inner side wall cut away as at 62, to permit of one end of the entrance of the track 43 to allow for the shifting of the track and further for the ingress and egress of the conveyer. The outer side wall of the station 56, has an opening 63, to provide clearance for that end of the track 43 which is extended through the station 56. Supported within the station 56, in proximity to the opening 63, is a pivoted yoke 64 having its base engaged by the hook 45 whereby one end of the track is loosely supported within the dumping station.

Supported within the dumping station 56, between the front and rear walls thereof, is a trip-bar 65, arranged in the path of the trip arm 53, whereby when the conveyer 47 enters the loading station the arm 53 engaging with the bar 65, will be shifted; under such conditions the cut-off 59, will be moved clear of the spout 58 and the contents of the conveyer 47 will be discharged into the hopper 57.

The dumping station 56 is supported upon four uprights 66, connected together by cross-braces 67, which are positioned in proximity to the spout 58.

Removably supported upon the braces 67 is an inclined chute 68 for conducting the material discharged from the loading station 56, into a tray 69, or into any other suitable receptacle.

It will be assumed that the parts are as illustrated in Fig. 5, which shows the conveyer receiving sand from the hopper 6 and the element 28 receiving sand from the hopper 6. The supply of sand from the hopper 6, into the element 28 is greater than the amount supplied to the conveyer 47. As soon as the weight of the sand in the element 28, overcomes the weight of the lowered end of the track 43 and conveyer 47, the element 28 moves downwardly whereby the lowered end of the shaft 43 is elevated, due to the upward movement of the slide 39, and when the said end of the track 43 is elevated the conveyer 47 is carried therewith. The lowering movement of the element 28 will cause the track 43 to extend at an inclination with respect to the loading and dumping stations, that is to say, the track will extend downwardly at an inclination from the loading station toward the dumping station. When the track 43 is in such position, the conveyer with its load will travel down the track by gravity and toward the dumping station. As it enters the dumping station the trip-arm 53 will be actuated and the load discharged from the conveyer into the hopper 57. The slide 39, owing to its weight and also owing to the

weight of the elevated end of the track 43, 65 will then move downwardly inclining in the opposite direction the track 43, whereby the latter will extend downwardly at an inclination from the dumping station to the loading station and under such conditions the conveyer will then travel by gravity back to the loading station. As the slide 39 moves downwardly the element 28 will move upwardly until it engages the trip arm 11. At this point the conveyer will be in a position 75 to receive a load. When the arm 11 is actuated the cut-off 9 will be shifted to open the spout 8, and the sand from the hopper 6 will be discharged into the conveyer and into the element 27.

What I claim is:

1. A sand toy comprising a loading station, a dumping station, a track connecting said stations together and shiftable alternately in opposite inclined planes, a gravity movable dumping conveyer traveling in alternate directions on said tracks with respect to the loading station and to the dumping station, and a vertically movable combined conveyer elevating and loading mechanism arranged within the loading station and connected with one end of said track to elevate said end as the mechanism moves downwardly.

2. A sand toy comprising a loading station, a dumping station, a track connecting said stations together and shiftable alternately in opposite inclined planes, a gravity movable dumping conveyer traveling in alternate directions on said tracks with respect to the loading station and to the dumping station, and a vertically movable combined conveyer elevating and loading mechanism arranged within the loading station and connected with one end of said track to elevate said end as the mechanism moves downwardly, said mechanism including a vertically movable element shifted downwardly by a supply of sand thereto during loading of the conveyer to elevate said end and shifted upwardly by said end to initial position when the contents of said elements have been discharged.

3. A sand toy comprising a loading station, a dumping station, a track connecting said stations together, and shiftable alternately in opposite inclined planes, a gravity movable dumping conveyer traveling in alternate directions on said tracks with respect to the loading station and to the dumping station, and a vertically movable combined conveyer elevating and loading mechanism arranged within the loading station and connected with one end of said track to elevate said end as the mechanism moves downwardly, said mechanism including a vertically movable element shifted downwardly by a supply of sand thereto

during loading of the conveyer to elevate said end and shifted upwardly by said end to initial position when the contents of said elements have been discharged, and means 5 for dumping said elements to permit of the latter to be elevated by said end.

4. A sand toy comprising a loading station, a dumping station, a track connecting said stations together, and shiftable alternately in opposite inclined planes, a gravity 10 movable dumping conveyer traveling in alternate directions on said tracks with respect to the loading station and to the dumping station, and a vertically movable 15 combined conveyer elevating and loading mechanism arranged within the loading station and connected with one end of said track to elevate said end as the mechanism moves downwardly, and means within the 20 dumping station for dumping said conveyer.

5. A sand toy comprising a loading station, a dumping station, a track connecting said stations together and shiftable alternately in opposite inclined planes, a gravity 25 movable dumping conveyer traveling in alternate directions on said tracks with respect to the loading station and to the dumping station, and a vertically movable combined 30 conveyer elevating and loading mechanism arranged within the loading station and connected with one end of said track to elevate said end as the mechanism moves downwardly, and means within the dumping station for dumping said conveyer, and means 35 connected with the dumping station for directing the material dumped from the conveyer therefrom.

6. A sand toy comprising a loading station, a dumping station, a track connecting 40 said stations together and shiftable alternately in opposite inclined planes, a gravity movable dumping conveyer traveling in alternate direction on said tracks with respect to the loading station and to the dumping 45 station, and a vertically movable combined conveyer elevating and loading mechanism arranged within the loading station and connected with one end of said track to elevate said end as the mechanism moves downwardly, said mechanism including a vertically 50 movable element shifted downwardly by a supply of sand thereto during loading of the conveyer to elevate said end and shifted upwardly by said end to initial position 55 when the contents of said elements have been discharged, and means within the dumping station for dumping said conveyer.

7. A sand toy comprising a loading station, a dumping station, a track connecting said 60 stations together and shiftable alternatively in opposite inclined planes, a gravity movable dumping conveyer traveling in alternate directions on said tracks with respect to the loading station and to the dumping station,

and a vertically movable combined conveyer 65 elevating and loading mechanism arranged within the loading station and connected with one end of said track to elevate said end as the mechanism moves downwardly, said mechanism including a vertically movable element shifted downwardly by a supply of sand thereto during loading of the conveyer to elevate said end and shifted upwardly by said end to initial position when the contents of said elements have been discharged and means within the dumping station for dumping said conveyer, and means connected with the dumping station for directing the material discharged from the 70 conveyer therefrom.

8. A sand toy comprising a track shiftable alternately in opposite inclined planes, a gravity movable dumping conveyer traveling in opposite directions on said track and a combined loading and elevating mechanism 85 for said conveyer, said mechanism connected to one end of said track and elevating the latter, and the conveyer when said mechanism is lowered, said end of said track lowered by the weight thereof when the conveyer is at the other end thereby elevating said mechanism.

9. A sand toy comprising a track shiftable alternately in opposite inclined planes, a gravity movable dumping conveyer traveling in opposite directions on said track and a combined loading and elevating mechanism for said conveyer, said mechanism connected to one end of said track and elevating the latter, and the conveyer when said mechanism is lowered, said end of said track lowered by the weight thereof when the conveyer is at the other end thereby elevating said mechanism, and means for dumping the 90 conveyer.

10. A sand toy comprising a hopper, chute connected therewith for directing discharge therefrom in two directions, means for normally closing said hopper, a track shiftable alternately in opposite inclined planes, a gravity movable dumping conveyer traveling upon said track and receiving its load from said hopper when said means is actuated, a vertically movable element connected with one end of said track, said element when at the limit of its upward movement actuating said means to open said hopper to receive material therefrom causing thereby the lowering thereof, the closing of the hopper and the elevating of said end of said track whereby the conveyer will travel upon the track by gravity.

11. A sand toy comprising a hopper, chute connected therewith for directing discharge therefrom in two directions, means for normally closing said hopper, a track shiftable alternately in opposite inclined planes, a gravity movable dumping conveyer travel-

ing upon said track and receiving its load from said hopper when said means is actuated, a vertically movable element connected with one end of said track, said element 5 when at the limit of its upward movement actuating said means to open said hopper to receive material therefrom causing thereby the lowering thereof, the closing of the hopper and the elevating of said end of said

track whereby the conveyer will travel upon 10 the track by gravity and means for dumping said element.

In testimony whereof I affix my signature in the presence of two witnesses.
